UNITED STATES PATENT OFFICE

JOSEPH FRED MERKEL, OF ROCHESTER, NEW YORK, ASSIGNOR TO GENERAL RAILWAY SIGNAL COMPANY, OF ROCHESTER, NEW YORK

ALTERNATING-CURRENT RELAY

Application filed August 31, 1926. Serial No. 132,835.

This invention relates to alternating current relays for railway signaling, and refers more particularly to a relay of the single element vane type.

The objects of this invention are to simplify and improve the construction of vane type alternating current relays so that they can be cheaply manufactured with a minimum of labor in assembly and adjustment; to provide a unitary type of structure for supporting and aligning the moving elements of the relay relative to the core and coil structure; to incorporate within the relay a simple form of spark gap lightning arrester for providing protection to all terminals and bearings; to make a vane in such form as to minimize the tendency to warp or distort due to local heating under energized conditions; to provide means for facilitating a predetermined adjustment of the contact fingers relative to their fixed contacts; and in several other particulars to be pointed out hereinafter, to arrange the proportion of parts to facilitate manufacture, inspection, and re-pair.

Further objects, purposes and characteristic features of this invention will appear as the description progresses.

By the way of illustration, one form of device embodying the present invention is shown in the accompanying drawings wherein:

Fig. 1 is a front elevation of a relay constructed in accordance with this invention, parts being shown in section and portions of the structure being removed to more clearly show the construction.

Fig. 2 is a side elevation of the device with parts shown in section and portions of the structure removed for more clearly showing the construction.

Fig. 3 is a sectional plan view on line 3—3 of Fig. 1, viewed in the direction of the arrows.

Fig. 4 is a section on line 4—4 of Fig. 2, viewed in the direction of the arrows.

Fig. 5 is a detailed plan view of one of the lightning arrester elements.

Fig. 6 is a side elevation of the magnetic core structure used in the relay.

Fig. 7 is a longitudinal sectional view through one of the terminal posts, with parts shown in elevation, and

Fig. 8 is a detailed side elevation of one of the supporting side plates of the device.

Referring to the drawings, the relay shown comprises a circular base 1, preferably a stamped product, formed with a flat shelf 2 around its outer circumference and having a central depression 3. The top plate 4 is circular in form and is made of porcelain or similar insulating material having the necessary strength and insulating property, and is likewise formed with a shelf 5 around its outer edge. The walls of the relay are formed of a cylindrical glass 6 which rests on gaskets 7 supported on the shelves on the top plate and base. The top plate and base are clamped together with the glass 6 between, by means of four through bolts 8 having suitable nuts on their ends.

For supporting the various elements of the relay, there are provided two spaced side plates 9 which are formed with their vertical edges half rounded in order to partly surround the connecting bolts 8 as most clearly shown in Fig. 3. These side plates are wholly supported from the top plate 4 by means of integral ears 10, through which the bolts 8 pass, the ears being clamped against the top plate by means of nuts 11 held from turning on the bolts 8 by means of flattened sides 12 on the side plates, and drawn up against the top plate by means of threaded washers 13 received on the bolts, and lodged in sockets or depressions in the top face of the top plate. These side plates are preferably stamped products and are cut away as shown in Fig. 8 to form somewhat resilient upstanding opposed arms 14, and cross straps 15, for a purpose to be later explained.

The magnetic core structure, Fig. 6, is built up of punched laminae shaped in the form of a C to provide a back yoke 16 and horizontal inturned legs 17 terminating adjacent each other for forming an air gap. Each lamina is sheared entirely through along a line 18 concentric with a central pivot bolt 19, to form one air gap per lamina, bolt 19 passing through the back strap of

the core, and the laminæ are stacked with successive laminæ having these air gaps at opposite sides of the bolt 19, to thereby form a hinged joint about the bolt. In this manner the core can be readily opened out about the bolt 19 so as to separate the legs 17 for facilitating mounting of coils thereon. The laminæ are held together by four tubular rivets 20 the ends of which are spun over, as shown in Fig. 3.

16. Clamp plates 21 of U-shape are clamped on either side of the core by means of bolts 22 passing through the rivets 20, and the clamp plates are formed with outwardly bulged bosses on their inner surfaces to accommodate the spun over ends of the rivets 20. Integral ears 23 are formed on the clamp plates for connecting the plates and the laminated core to the side plates 9 by means of bolts 24 so that the core is wholly supported from these side plates 9.

17. The pole faces of the core legs 17, are slotted in the usual manner and provided with shade rings 25 which project by the amount of their thickness to one side of the core, in the usual manner. Rivets 26 fasten the shade rings to the laminated core and also connect leaf springs 27 to the core on the side opposite the shade rings, which leaf springs are normally biased outwardly away from the side of the core.

18. The coils 28 are wound on spools of suitable insulating material such as molded bakelite or the like, the apertures in the spools being made large enough to slip over the ends of the core legs 17 and the projecting shade rings. After slipping the coils over the ends of the core legs the springs 27 force the coils sidewise to position them between the projections formed by the shade rings and the clamp plates 21, so as to hold them firmly in place and prevent any sliding on the core, as is best shown in Fig. 3.

19. The vane 29 is made of suitable cheap material, preferably aluminum, and is fastened at its upper edge at several points by means of screws 30, to the lower edge of an arm 31 projecting from and formed integral with a counter-weight 32 which is held on the vane spindle 33 by means of a set screw 34. The vane is thus spaced away from its spindle so as to leave both its inner and outer edges free and due to this spacing, heat generated in the vane by eddy currents during its energized position can be much more readily dissipated and thus prevent warping of the vane. This is of very considerable importance in view of the fact that the relay is energized during the major part of the time when in service.

20. The vane spindle 33 is pivoted to the side plates 9, between the upper ends of the resilient arms 14, in anti-friction bearing comprising bushings 34 fixed in the side plates and having threaded bosses to receive bear-

ing screws 35 having sockets at their inner ends supporting sleeve jewel bearings 36 and jewel step bearings 37 for receiving the reduced trunnions 38 of the vane spindle. Lock nuts 39 are provided for holding the bearing screws 35 in set position. The vane spindle, supported by the resilient arms 14 of the side plates, is thus resiliently mounted so that wear on the bearings and trunnions will be automatically compensated for by the resiliency of the arms. Furthermore, it has been found in practice that with a rigid mounting for the vane spindle, the jewel step bearings are often cracked during adjustment of the spindle bearings due to tightening up of the bearing screws to too great an extent. The resilient mounting provided in this device effectually prevents such cracking of the bearings, the spring arms automatically taking up any excess pressure on the bearings if the screws 35 be adjusted too tightly.

21. The carrier bar 40 is formed of suitable insulating material molded directly around a spindle 41 pivoted between the straps 15 of the side plates 9, and supported in suitable adjustable bearings 42 which can also be jeweled in the same manner as for the vane spindle, if so desired. As in the case with the vane spindle the bearings for the spindle 41 are readily adjustable. The carrier bar 40 has an integral arm 43 formed thereon to which is connected a depending bifurcated arm or fork 44, the lower free end of each branch of the fork being bent back parallel to itself, as at 45 to form bearing supports for rollers 46 mounted on pins passing through the bent ends of the fork. Formed integrally with the counter-weight 32 is an actuating cam 47 arranged to fit snugly between the depending arms of the fork 44 and bear at opposite sides against the rollers 46, whereby oscillation of the vane spindle will cause the cam to oscillate the carrier bar 40.

22. The contact fingers 48, carrying the movable front and back contacts, are preferably made from a single piece 49 of suitable resilient material, backed up by a relatively rigid retaining member 50 to prevent flexing of the finger in one direction, and are supplied with suitable contacts 51 in the usual manner. The contact fingers are fastened to the carrier bar by passing them over studs 52 molded in the insulating material forming the bar and clamped thereagainst by means of nuts 52¹ screwed onto the studs. The carrier bar has depressions formed in its lower face around the studs 52 for receiving the contact fingers, and aiding in the assembly, as shown at 53 in Fig. 4.

23. The terminal or binding posts for supporting the fixed contacts, both front and back, and lead in wires for the contact fingers, are supported in the top plate 4 and 120

are shown most clearly in Fig. 7. Each terminal post includes a threaded stem 54 with an enlarged head 55 having at one end a hexagonal portion 56 snugly fitting into a groove 57 formed in the lower face of the top plate 4 and preventing turning of the stem 54 in the top plate. The post is clamped to the top plate by means of a threaded washer 58 received in, and bearing against the bottom of a socket 58¹ formed in the upper surface of the top plate, to firmly clamp the plate 4 between the washer 58 and the hexagonal head portion 56 of the stem. A washer 59 covers the socket in the top plate and is held in position by a suitable lock nut as shown while the upper portion of the threaded stem 54 receives the usual washers and nuts for connecting lead-in wires.

20 A threaded bore in the enlarged head 55 of each post carrying a fixed contact, receives the threaded stem 60 of the fixed contact which is preferably formed of a cylindrical block of carbon 61, impregnated with a small 25 percentage of copper, and gripped in a slotted cup 62 carried by the stem 60, the rim of the cup being slotted to more readily permit its being crimped in to firmly hold the carbon block in place. A lock nut 62¹ operates to hold the stem in its adjusted position. It will be noted that with the construction described above the fixed contacts can be readily adjusted in position without disturbing the clamping of the posts to the top plate. 30 The posts for connecting lead-in wires to the contact fingers, are constructed as just described, except for the fixed contacts being replaced by screws and nuts 62¹ for connection of lightning arrester arms and wires 35 thereto.

Extending between the side plates 9 are two rods 63 positioned just below the top plate and in proximity to the inner ends of the various terminal posts. A metal strap 45 81 connects one of these rods to a ground post 82 carried by the top plate. In this manner the side plates and rods 63 are electrically interconnected and the whole is grounded.

50 Connected to the inner end of each of the terminal posts are conducting arms 64 or 65 extending toward the rods 63 but spaced therefrom to form an air gap. The arms 64 are connected to the posts carrying the fixed 55 contacts, while the pairs of arms 65, are connected to posts carrying lead-in wires for the contact fingers. By bending these arms, the size of the air gaps between the arms and the rods can be readily adjusted.

50 Each arm 64 is connected to a contact carrying terminal post by means of a perforated portion 66 received on the stem 60 of the fixed contact and positioned between the hexagonal portion 56 and the lock nut 5 62¹. The pairs of diametrically opposed out-

standing ears 67 are formed on the portion 66, one pair of which is bent upwardly about the hexagonal portion 56 of the head on stem 60, while the other pair is bent downwardly around the lock nut 62¹ thus holding 70 the projecting arm 64 in fixed position and acting to lock the lock nut 62¹ in place.

Each pair of arms 65 is formed to extend to opposite sides of a perforated portion 68 which has a single pair of diametrically opposed ears 69. Each portion 68 is fastened to the inner end of a binding post connected to the contact fingers, by means of a nut and screw 62¹, with the ears 69 bent upwardly about the nut in order to lock it in position, 80 as shown in Fig. 4.

With the construction just described it will be seen that an effective spark gap lightning arrester is provided for all of the terminal posts and also for the bearings of the vane 85 and carrier bar spindles. It is of course understood that in each of the circuits protected by this lightning arrester there will be sufficient inductance to force the lightning to discharge across the gap between a rod 90 63 and the adjacent arm and then to ground, rather than through the contacts and contact fingers. The lightning will also take a path through the side plates 9 and the ground connection rather than across the bearings 95 for the spindles 33 and 41.

In order to bring the vane 29 to a position of rest in a gradual manner and without shock in its de-energized position, a back stop is provided. This back stop, as most clearly shown in Fig. 1, comprises two spaced, parallel, resilient arms 71, formed of a fairly stiff wire in the example shown, fastened at their upper ends to the top plate 4 by means of bolts 72, and bent over on themselves 100 at their lower ends, to form elongated downwardly inclined narrow loops 73, furnishing bearings for a roller 74 trunnion therein. The roller 74 is positioned directly in the path of travel of the vane, and is forced from the lower end of the loops 73 to the upper end while bringing the vane to rest. There is also a certain amount of sliding movement 110 between the roller 74 and the vane which sets up some little friction and thereby dissipates 115 a certain amount of the energy of the vane. It is of importance to have the roller 74 supported in a resilient bracket, so that the bracket itself can aid in cushioning the motion of the vane in bringing it to rest.

In a like manner, in order to bring the vane gradually to rest, without shock, in its energized position (the dotted line position of Fig. 1) a front stop is provided which comprises a flat strap 75 of rigid material fastened at the upper end by bolt 76 to the top plate and carrying at its lower end, directly in the path of travel of the vane, a resilient arm 77 bent as shown in the drawing, and normally biased away from the bracket 75. 120 125 130

When the vane contacts with the arm 77, the arm is first bent towards its bracket as a cantilever, until the portion 78 thereof bears against bracket 75, after which the spring arm exerts a greater resistance to bending, by exerting a truss resistance and thus brings the vane to a position of rest.

In practice it has been found undesirable to use a stop having a dead weight such as the roller 74 as a front stop, since in its energized position, the vane is driven with a rapidly fluctuating force and this normally sets up a vibration of the vane which causes very considerable wear on the bearings of the vane spindle 33. By using the spring arm 77 as described above, this vibration of the vane is damped and the vane is brought to a position of rest in the energized position. Furthermore on de-energizing the relay the spring arm 77 biases the vane towards its other extreme position and aids in preventing any sticking of the parts.

In adjusting the contact fingers, it is desirable to position them so that they first contact with the stationary back and front contacts, some little time before the vane reaches either of its extreme positions. In order to aid in this adjustment and to permit a uniform adjustment of the fingers, two indicating marks 79 and 80 are placed on one side of the vane. The contact fingers 48 are bent so as to first touch the fixed contacts when one of the marks 79 or 80 is brought opposite the left edge of a side plate 9, as viewed in Fig. 1. An indicating pointer could equally well be used, if desired, and be attached to some fixed part of the relay. The mark 79 is used for adjusting the fingers which co-act with the front contacts while the mark 80 is used for adjusting those co-acting with the back contacts. The travel of the vane comprised between the extreme positions and the points at which the marks 79 and 80 register with the edge of the side plate, operates to press the movable contacts 51 against the stationary contacts to cause the desired wipe and pressure.

An inspection of Fig. 2 will show that the vane and the coils and core are so arranged as to permit an unobstructed view through the air gap at both sides of the vane, on looking through opposite side walls of the casing. This permits ready inspection of the relay in order to ascertain whether or not any obstruction has lodged between the vane and the pole faces, without any necessity for taking the relay apart. By positioning the core with its back strap below the vane and at right angles thereto, the core presents no interference to an unobstructed view throughout the entire extent of the air gap.

The above detailed description of one form which the present invention may assume has been given by way of illustration only and is not intended in any manner whatsoever,

in a limiting sense. Various changes, rearrangements of parts, and modifications, as come within the scope of the appended claims, can be made without departing from the present invention.

I now claim:—

1. In a relay, a top plate, spaced side plates carried by the top plate, a horizontal carrier bar pivoted to the side plates, a vane spindle pivoted to the side plates and substantially parallel to the carrier bar, a vane on the spindle, portions of each side plate being cut away to form upstanding, integral, resilient arms between which the vane spindle is mounted, and an operating connection between the carrier bar and the vane spindle.

2. In a relay, a top plate, spaced side plates carried by the top plate, a horizontal carrier bar pivoted to the side plates, a vane spindle pivoted to the side plates and substantially parallel to the carrier bar, a vane on the spindle, portions of each side plate being cut away to form upstanding, integral, resilient arms between which the vane spindle is mounted, and an operating connection between the carrier bar and the vane spindle, and jewelled step bearings for the trunnions of the vane spindle.

3. In a relay, side support plates, integral, spaced, resilient arms extending from the plates, bearings in the free ends of the arms, and a spindle pivoted in the bearings.

4. In a relay, side support plates, integral spaced resilient arms extending from the plates, jewelled step bearings in the free ends of the arms, and a vane spindle pivoted in the bearings.

5. In a relay, a top plate, spaced side plates suspended from the top plate, a horizontal carrier bar spindle pivoted in the side plates, a vane spindle pivoted in the side plates parallel to the carrier bar spindle, induction means supported by the side plates, a vane on the vane spindle cooperated with the induction means, and an operating connection between the vane spindle and the carrier bar spindle.

6. In a relay, a pivoted carrier bar, a plurality of contact fingers on the bar, an operating member on the bar having a forked lower end, a pivoted vane spindle, a counter-weight fixed to the spindle, an extending arm integral with the counter-weight, a vane fixed to the arm and wholly spaced from the spindle, and an operating cam integral with the counter-weight for co-acting with the forked lower end of said operating member to operatively interconnect the carrier bar and the spindle.

7. In a relay, a pivoted carrier bar, a pivoted vane spindle, substantially parallel with said carrier bar, an arm extending from the spindle, a vane fastened to the arm in spaced relation to the spindle, an operating connection between the spindle and carrier bar,

and induction means forming an air gap through which the vane is positioned to move.

8. In an alternating current relay, a laminated core defining a narrow air gap, coils on the core, a pivot pin passing through all of the laminae of the core, successive laminae being sheared entirely through, on opposite sides of the pivot pin, along lines concentric with the axis of the pin, so as to form a hinged joint about the pin to permit opening out the core for facilitating sliding of the coils onto the core.

9. In an electro-magnet, a substantially C shaped laminated core, shade rings in the ends of the core and projecting to one side thereof, a clamp plate fastened to each side of the core and forming projections spaced from the shade rings, a coil having an opening large enough to be slipped over an end of the core and its projecting shade ring, and means biasing the coil to one side of the core to hold it between the projections formed by the shade ring and clamp plate.

10. In an electro-magnet, a substantially C shaped laminated core, shade rings in the ends of the core and projecting to one side thereof, a clamp plate fastened to each side of the core and forming projections spaced from the shade rings, a coil having an opening large enough to be slipped over an end of the core and its projecting shade ring, a leaf spring fixed to the core and sprung outwardly thereof for biasing the coil to one side of the core to hold it between the projections formed by the shade ring and clamp plate.

11. An electro-magnet core having a straight end, a shade ring in, and projecting to one side of, said end, a clamp plate bolted to the side of the core and projecting therefrom at a point spaced from the shade ring, a closed coil slideable over the end of the core and shade ring, and means biasing the coil sidewise of the core to hold it between the projections formed by the shade ring and clamp plate.

12. In a relay, a casing, a spindle pivotally mounted in the casing, a swinging vane fastened thereto, and a back stop for the vane, including, two spaced resilient arms fixed to the casing with the end of each arm bent back on itself to form parallel downwardly inclined elongated loops, and a roller slidably trunnioned in the loops and in the path of the swinging vane.

13. In a relay, a casing, a vane pivoted to swing in the casing, and a front stop for the vane including, a rigid bracket fixed to the casing and projecting into the path of the swinging vane, a resilient arm fixed to the bracket with its free end spaced therefrom, the resilient arm being directed toward, and in the path of, the vane, in advance of the rigid bracket, for resiliently and positively arresting motion of the vane in one direction.

14. In a relay, a casing, a vane pivoted to swing in the casing, a front stop for the vane including, a rigid bracket fixed to the casing and projecting into the path of the swinging vane, a resilient arm fixed to the bracket with its free end spaced therefrom, the resilient arm being directed toward, and in the path of, the vane, and shaped to first act as a resilient cantilever, and then as a resilient truss, when pushed towards the rigid bracket, whereby to act as a vane stop of variable resistance.

15. In a relay, a casing, a carrier bar mounted on trunnions in the casing, contact fingers on the carrier bar, a top plate on the casing, terminal posts in the top plate carrying fixed contacts and electrical connections for the contact fingers, conducting rods passing adjacent the terminal posts and connected across the casing, an arm connected to each post and terminating adjacent a conducting rod to furnish a spark gap, and means for grounding the casing, whereby to furnish a spark gap lightning arrester for each terminal post and trunnion.

16. In a relay, a casing, a carrier bar mounted on trunnions in the casing, contact fingers on the carrier bar, a top plate on the casing, terminal posts in the top plate carrying fixed contacts and electrical connections for the contact fingers, conducting rods passing adjacent the terminal posts and connected across the casing, a flexible arm connected to each post and terminating just short of a rod for furnishing an adjustable spark gap, and means for grounding the casing, whereby to furnish a spark gap lightning arrester for each terminal post and trunnion.

17. In a relay, a metal frame, an insulating top plate on the frame, terminal posts in the top plate, conducting means connected to the frame and passing adjacent the terminal posts, a conducting arm connected to each post and terminating adjacent the conducting means to form a spark gap, and means for grounding the frame.

18. In a relay, a metal frame, an insulating top plate on the frame, terminal posts in the top plate, conducting means connected to the frame and passing adjacent the terminal posts, a conducting arm connected to each post and terminating adjacent the conducting means to form a spark gap, each arm comprising, a perforated disc received on a post and two pairs of opposed projecting fingers, a nut for locking each disc to the post, one pair of fingers being bent about the post, and the outer post being bent about said nut, whereby to hold each arm in fixed position and lock the nut on the post.

19. In a relay, a casing, a carrier bar pivoted horizontally in the casing, a vane spindle pivoted in the casing and substantially parallel with the carrier bar, a counter-weight fastened to said spindle, a vane on said coun-

- ter-weight, induction means for swinging the vane, a depending fork on the carrier bar, the ends of the fork being bent back on themselves in spaced relation, pins passing through the spaced end portions, rollers mounted on the pins and a cam integral with the counter-weight and in constant operative engagement with the rollers of the fork for rocking the carrier bar.
20. In a relay, a frame, a top plate on the frame, stationary contacts carried by the top plate, a spindle pivoted in the frame, a carrier bar formed of insulating material moulded directly on the spindle, and contact fingers on the carrier bar cooperating with the stationary contacts.
21. In a relay, a frame, a top plate on the frame, stationary contacts carried by the top plate, a spindle pivoted in the frame, a carrier bar formed of insulating material moulded directly on the spindle, contact fingers carried by, and extending to either side of the bar, and cooperating with the stationary contacts, each contact finger being formed of a single piece of resilient material connected to a backing member of stiff material arranged to prevent flexing of the finger in one direction.
22. In a relay, a frame, a top plate on the frame, stationary contacts carried by the top plate, a spindle pivoted in the frame, a carrier bar formed of insulating material moulded directly on the spindle, mounting slots in the carrier bar, projecting threaded studs moulded in the bar at the mounting slots and contact fingers positioned in the mounting slots and held to the carrier bar by nuts threaded on the studs.
23. In a relay, a casing, a carrier bar pivoted in the casing, contact fingers mounted on the carrier bar, a top plate for the casing, grooves in the under surface of the top plate, and terminal posts in the top plate carrying stationary contacts cooperating with the contact fingers, each terminal post and stationary contact including, a threaded stem passing through the top plate, a flat sided head at one end thereof fitting into one of the grooves in the under side of the top plate to prevent turning of the stem in the plate, a socket in the upper side of the top plate, a nut threaded on the stem and bearing against the bottom of said socket to clamp the top plate between the nut and the stem head, a washer on the stem covering the socket and nut, wire attaching means on the stem, a threaded bore in the stem head and inner end of the stem, a threaded shank in the threaded bore carrying a stationary contact, and a nut for locking the shank in the threaded bore.
24. In a relay, a casing, a carrier bar pivoted in the casing, contact fingers mounted on the carrier bar, a top plate for the casing, grooves in the under surface of the top plate, and terminal posts in the top plate carrying stationary contacts cooperating with the contact fingers, each terminal post and stationary contact including, a threaded stem passing through the top plate, a flat sided head on the stem positioned in one of the grooves in the inner face of the top plate, a socket in the outer face of the plate around the stem, a nut on the stem bearing against the bottom of the socket and drawing the stem head against the plate, and a contact cup carried on a stem screwed into the stem head.
25. In a relay, a casing comprising, a top plate, a base and transparent side plates, a horizontal vane spindle, a vane on said spindle, and an electro-magnet having poles terminated adjacent each other on opposite sides of the vane to form an air gap, the back strap of the magnet being vertically below the vane shaft whereby to permit an unobstructed view through the entire air gap from one side of the casing through the opposite side.
- In testimony whereof I hereby affix my signature.
- JOSEPH FRED MERKEL.
